UNITED STATES PATENT OFFICE

EDWARD A. MALM, OF WADENA, MINNESOTA

RAIN DRAIN FOR WINDOW SCREENS

Application filed December 2, 1927. Serial No. 237,271.

The object of my invention is the provision of a screen drain to be located in the bottom rail of wood window screens for the purpose of draining out any water which would drive through the screen during rainstorms or otherwise. During rainy seasons wood screens swell tight into window frame causing water which enters inside of window screens to lodge and back up over inside window sill, thus spoiling inside wall decorations under the window. My invention is a preventive by allowing the water to drain out before it backs up far enough to do any damage.

15 To the attainment of the foregoing, the invention consists in the improvement as hereinafter described and definitely claimed.

In the accompanying drawings, forming part of this specification:

20 Figure 1, is a perspective fragmentary sectional view showing a window sill, window screen and method of mounting my novel rain drain.

Figure 2, is a sectional view of my rain drain, taken on line 1—1 of Figure 1.

Figure 3, is an end view of my novel rain drain showing the plurality of perforations.

Similar numerals of reference designate corresponding parts in all of the views of 30 the drawings.

Referring to the drawings, 5 represents the ordinary window sill. The bottom rail of a window screen 6 is of the ordinary construction. Midway the ends of the bottom rail 35 of the screen a hole 7 is bored into which my novel drain is inserted.

My novel drain comprises a tubular shell body 8, having a flange 9, on one end to hold the tubular shell in place. The opposite 40 end of the tubular shell is provided with a plurality of perforations 10. A raised projection 11 is provided on the body 8, and holds the drain in rigid position when driven into the hole 7.

45 It will be noted that with my improvement, water will be prevented from backing over inside window sill, spoiling interior wall decoration, also so constructed that flies and insects are kept from passing through.

50 I have entered into a detailed description

of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of invention various changes and modifications may be made such as fall 55 within the scope of my invention as defined in my appended claim.

Having described my invention, what I claim and desire to secure by Letters Patent is:—

A rain drain for window screens, comprising a unit consisting of a tubular shell, a flanged end, a perforated end and an outwardly raised projection on the shell body.

In testimony whereof I affix my signature. 70
EDWARD A. MALM.
